UNITED STATES PATENT OFFICE

ERNEST S. ROE, OF PLYMOUTH, MICHIGAN, ASSIGNOR TO THE KING MANUFACTURING COMPANY, OF PLYMOUTH, MICHIGAN, A CORPORATION OF MICHIGAN

SPRING AIR GUN

Application filed February 6, 1928. Serial No. 252,307.

This invention relates to spring air guns of that type which simulate the appearance of the so-called pump gun and in which the spring is compressed by the sliding of the 5 pump handle on the barrel.

It is one of the primary objects of the present invention to provide a gun of the foregoing construction capable of producing a report simulating that of a rifle without 10 discharging the projectile from the barrel.

In the type of pop guns heretofore used considerable inconvenience has been experienced in the necessity of breaking the gun adjacent the stock thereof for compressing 15 the spring to place the gun in cocked position. Moreover in this later type of construction it has been usually necessary for the operator to place the projectile within the barrel so that upon firing the gun the projectile will 20 be discharged from the barrel to produce the desired report. While the foregoing arrangement is satisfactory for producing the desired results it has been found objectionable not only due to the time required to 25 place the gun in firing condition but also due to the number of parts necessary for the efficient operation of the gun.

The present invention contemplates eliminating the foregoing disadvantages by providing a pop gun having the pump type operating means for compressing the spring and having means depending upon the operation of the pump for automatically inserting the projectile in the air chamber.

Many of the advantages and much of the commercial value and acceptability of the invention is attributed to the novel construction of the gun, these advantages being obtained particularly because of the simplicity of the 35 construction and the minimum number of parts employed. This enables the entire construction to be economically and quickly manufactured and easily assembled and renders the same strong and durable. The invention 40 therefore depends for some of its advantages upon the specific details of construction which will be made more apparent as this description proceeds especially when considered in connection with the accompanying 45 drawings wherein

Figure 1 is a side elevation of a gun embodying my invention.

Figure 2 is a sectional view of the gun showing the spring in released position.

Figure 3 is a view similar to Figure 2 55 showing the spring compressed and the parts in position ready for firing, and

Figure 4 is a sectional view taken on the line 4—4 of Figure 2.

Figure 5 is a sectional view taken on the 60 line 5—5 of Figure 3.

Referring now more particularly to the drawing wherein like reference characters indicate like parts, it will be noted that in Figure 1 there is illustrated an air gun 10 having 65 a barrel 11 and a stock 12. Sleeved within the barrel 11 and secured thereto adjacent the rear end thereof is a tubular member 13 normally sealed at the forward end thereof by means of a suitable projectile 13' which co- 70 operates with the tubular member to form an air compression chamber. Slidably arranged within this chamber for compressing the air therein against the projectile 13' is a plunger 14 having a shank portion 15 slidably mounted within the trigger housing 16 and terminating at the rear end thereof in a hooked portion 17. The hooked portion 17 performs a dual function in the operation of the gun and in addition to engaging behind the rivet 80 18 for limiting the forward movement of the plunger, is of sufficient length to engage behind the projection 19 of the trigger 20, in the cocked position of the gun as shown in Figure 3. For normally urging the plunger to 85 the position illustrated in Figure 2 I provide a coil spring 21 surrounding the shank portion 15 of the plunger and engageable at the forward end with the plunger and at the rear end with the trigger housing.

In order to cock the gun, or in other words, move the plunger rearwardly to the extent that the hooked portion 17 engages behind the projection 19 of the trigger 20 and thereby compress the spring 21, I provide the mechanism indicated generally by the reference numeral 22. This mechanism comprises the pump handle 23 having the circumferentially extending groove 24 therein. Arranged with in this groove is an annular member 25 hav- 95 100

ing a lateral projection 26 terminating in an upwardly extending portion 27. As shown this latter portion projects through an elongated slot 28 formed in the bottom of the barrel 11 adjacent the tubular air chamber 13 and is formed with a diameter slightly smaller than the interior diameter of the barrel 11. With this arrangement of parts it will be noted that the portion 27 performs three distinct functions in the operation of the gun, first, slidably supports the forward end of the pump handle upon the barrel; second, forms an abutment for the projectile upon firing the gun to retain the projectile within the barrel, and third, operates upon moving the pump handle rearwardly to positively engage the projectile and move the same into sealing engagement with the forward end of the compression chamber. Thus a triple function is attributed to this portion of the apparatus.

For connecting the pump handle 23 with the plunger I provide a rod 29 having the substantially flat portion 30 at the forward end thereof embedded within the handle 23 and cut away as at 31 for receiving a portion of the annular member 25. The rear end of the rod 29 is preferably offset as indicated at 32 and is adapted to project into the trigger housing 16 and engage the hooked portion 17 of the plunger 14. In order to normally maintain the pump handle and rod 29 in their extreme forward or inoperative positions the coil spring 33 is provided. As shown, this spring is secured at the forward end to the barrel and at the rear end to the extension 29 carried by the pump handle 23, the arrangement being that upon moving the handle 23 rearwardly to compress the spring 21 the spring 33 is placed under tension so that after the gun has been cocked the handle 23 upon being released by the operator will instantaneously return to its original or inoperative position.

Referring now to the operation of the device and assuming that the several parts thereof are in the position illustrated in Figure 2 and it is desired to place the gun in firing condition, by compressing the spring 21, the pump handle 23 carrying the rod 29 is moved rearwardly to the extent that the offset portion 32 of the latter engages the hooked portion 17 depending from the shank 16 of the plunger and moves the latter rearwardly to compress the spring 21 and engage the hooked portion aforesaid behind the projection 19 on the trigger 20. The latter is normally maintained in the path of the hooked portion by means of the spring 34 engageable at one end in the recess 35 and at the opposite end with the forward end of the stock 12. As heretofore pointed out during the compressing of the spring 21 the extension 27 carried by the handle 23 will operate to move the projectile 13' into sealing engagement with the air compression chamber. With the parts

in this position and it is desired to discharge the gun the trigger is moved rearwardly about the pivotal connection thereof to the barrel until the projection 19 releases the hooked portion 17 at which time the plunger will move forwardly instantaneously under the action of the spring 21 and compress the air contained within the chamber 13 to such an extent that the projectile will be forced from the end of the chamber permitting the air to escape into the barrel 11 and through the elongated slot 28 therein producing the desired report. Upon discharging the projectile from the end of the air compression chamber the former will strike the extension 27 and accordingly be prevented from escaping to the exterior of the barrel. If desired, a suitable opening 36 may be provided on the top of the barrel 11 adjacent the chamber 13 so that the operator may determine whether or not the projectile is in proper sealing engagement with the chamber.

Thus from the foregoing it will be apparent that the herein described arrangement offers the possibility of using a novel type of pump actuating mechanism for simultaneously compressing the spring of a pop gun and loading the same in which the usual folding links and their accompanying inefficiencies are dispensed with and one in which the frequency of operation is greatly increased owing to the comparatively short time required to place the gun in firing condition.

Another novel feature of construction of this invention, which contributes materially to the reduction in cost of manufacture and to the general appearance of the gun, is the provision of a trigger member formed from a single sheet of metal and having a portion simulating the usual trigger guard construction.

What I claim as my invention is:

1. In an air gun, the combination with a barrel having an air chamber therein and an elongated slot adjacent to said air chamber, of a projectile adapted to close said chamber, a spring actuated plunger for compressing the air within said chamber and discharging the said projectile therefrom, and compression mechanism for said spring including a pump handle having a projection extending through said slot and terminating within said barrel in an enlarged portion for slidably supporting the handle upon the barrel, said enlarged portion also being operable in one position of the handle to form a stop for said projectile and operable in another position of the handle to move the projectile into sealing engagement with the chamber.

2. In an air gun, the combination with a barrel having an air chamber therein, of a member adapted to close one end of said chamber, a spring actuated plunger for com-

pressing the air within the chamber, compression mechanism for said spring including, a pump handle, an element operatively connected to the handle and engageable with the plunger for actuating the same to compress the spring, and a second element connected to the handle for slidably supporting the same upon the barrel and having a portion projecting into the barrel and operable upon movement of the handle in compressing the spring to engage the member aforesaid and move the same into sealing engagement with the chamber, said second element also having a portion engaging and securing the first mentioned element to the handle.

3. In an air gun, the combination with a barrel having an air chamber therein, of a member adapted to close one end of the chamber, a spring actuated plunger for compressing the air within the chamber, and compression mechanism for the aforesaid spring including, a pump handle, a longitudinally extending rod extending rearwardly from said handle and engageable with the plunger for actuating the same to compress the spring, and an element connected to the handle for slidably supporting the same upon the barrel and having a portion extending into the barrel operable upon movement of the handle in compressing the spring to engage the member aforesaid and move the same into sealing engagement with the chamber, said element engaging said rod for securing the same to the handle.

4. In an air gun, the combination with a barrel having an air chamber, of a member adapted to close one end of said chamber, a spring actuated plunger for compressing the air within said chamber, compression mechanism for said spring including a pump handle, an element projecting from said pump handle and engageable with the plunger for actuating the same to compress the spring, and a member for slidably supporting the handle upon the barrel having a portion extending into the barrel and engageable with the closure member aforesaid for moving the same into sealing engagement with the chamber, said member having a second portion embracing the handle and engaging the element aforesaid for securing the latter to the handle.

In testimony whereof I affix my signature.
ERNEST S. ROE.
